UNITED STATES PATENT OFFICE

2,249,773

METHOD AND MEANS FOR GUMMING EN-
VELOPES AND SIMILAR SHEET MATE-
RIALSJohn A. Mattera, New York, N. Y., assignor to
Envelope Machine Corp., a corporation of New
York

Application July 19, 1939, Serial No. 285,332

15 Claims. (Cl. 93—62)

The present invention relates to a gumming machine and procedure and it particularly relates to a gumming and printing machine and procedure to be utilized in making envelopes.

Although the present invention will be particularly described in connection with the gumming and/or printing of envelopes, it is to be understood that it has many broader applications, the gumming and printing of envelopes merely being given by way of specific illustration.

In connection with envelopes it is usually necessary to utilize different types of gum or adhesive solutions for attachment of the transparent or glassine window and for attachment of the body of the envelope.

Considerable difficulty is experienced in securing proper application of these gums or adhesives and where reciprocatory adhesive applicators are utilized for applying the gum, special constructions must be provided so that the different types of gums may be readily applied and the reciprocatory mechanism is usually quite cumbersome and expensive and subject to getting out of order.

Moreover with such reciprocatory apparatus direct application of a gum from a pressure picker member to an envelope or similar piece of paper to receive the gum is necessary, and this direct application has not been found to be most satisfactory and it has not been most readily possible to control the amount of gum applied thereby, particularly when the reciprocating parts have been subjected to a little wear.

Moreover it has not been found readily possible to print the envelope in connection with the application of the adhesive, and as a result it was necessary to subject the envelope to a number of imprinting operations, one or more applications being for the application of the different types of gum for attachment of the body flaps, the sealing flap and/or the transparent window and one or more applications being for imprinting the body of the envelope with descriptive matter in one or more colors.

It is therefore among the objects of the present invention to provide an improved process and mechanism for applying gum or adhesive solution to envelopes and similar papers or fabrics in the process of manufacture, which will more accurately control the amount of gum applied, which will most satisfactorily apply the gum in desired areas, which will enable simultaneous printing of the envelope with one or more colors and which will produce the envelopes or other

imprinted materials at greater speed and at decreased cost.

In accomplishing the above objects, it has been found most satisfactory to make the device of the rotary type and it is a further object of the present invention to employ an improved rotary apparatus for imprinting envelopes and similar sheet material with adhesive, as well as with ink, which device will be widely adapted for printing and manufacturing different types of envelopes at high speeds, whether of the penny saving type or of the standard type and with or without a window. It is particularly desirable to accomplish these objects by an offsetting procedure in which the adhesive will be offset upon a rotary carrier for the envelope blank against which the envelope blank will be pressed and by which it will be carried.

Still further objects and advantages will appear from the more detailed description set forth below, it being understood, however, that this more detailed description is given by way of illustration, since various changes therein may be made by those skilled in the art without departing from the scope and spirit of the invention.

In accomplishing the above objects it has been found most satisfactory according to one embodiment of the present invention to utilize a partial cylindrical shell for application of the gum to the envelope, to which shell adhesive may be suitably transferred by an offset arrangement so that it will carry in suitable positions upon its surface one type of an edible quick drying gum or adhesive for the flap which is to be moistened by the user of the envelope and the other type of slow drying gum or adhesive to be utilized in connecting the side flaps in position.

Desirably these adhesive or gum solutions may be applied from a box or boxes containing the liquid adhesive material, from which box or boxes by one or more rollers the adhesive will be carried to an embossed or fragmentary roller having an embossment taking the shape of the areas on shell and the envelope, which are to receive the gum.

The embossments are so arranged and/or these rollers are so cut out that they will not interfere with one another or cause the gum to smear when applied to the main carrying cylinder. The blanks for the envelopes may be fed one by one by suction or suitable feeding mechanisms to the main carrying cylindrical shell where they will take up the gum which has already been applied to the surface of the cylinder.

At the same time as soon as the gum has been

applied to the rear face of the envelope blank, the front face of the envelope blank may be imprinted with one or more colors by a printing mechanism and after this operation has been completed, the envelope then may be taken away from the main cylinder to the folding mechanism.

Where it is desired to include a window in the envelope, the edges of the window patch may be gummed and fed onto the main carrying cylinder or shell before the envelope blank is placed upon said main cylinder or shell. However it has usually been found more desirable to apply the window in a subsequent operation following the imprinting and gumming of the edges of the window cut out in the envelope.

In transferring the envelope blank to the cylinder, reciprocatory suction fingers have been found to be quite satisfactory, but in holding the envelope in position to receive the gum and ink imprinting, it has been found most desirable to have a positive grip on the edge of the envelope to assure that the gum and ink will be applied at the proper places and in the proper register.

Referring to the drawings which illustrate several of the various possible embodiments of the present invention, but to which the present invention is by no means restricted, since the drawings are merely by way of illustration and not by way of limitation,

Fig. 1 is a side elevational view of one embodiment of the present invention showing the stack, the main carrier shell element and the gumming and printing arrangements,

Fig. 2 is a top plan view upon the line 2-2 of Fig. 1, showing the main carrier constructions and associated mechanisms,

Fig. 3 is a side sectional view upon the line 3-3 of Fig. 2,

Fig. 4 is a perspective view with part of the apparatus broken away, illustrating the operating mechanism for the suctioner devices and also the gripper devices,

Fig. 5 is a layout of a window type envelope which may be gummed with the apparatus of Figs. 1 to 4,

Fig. 6 is a side sectional view upon the line 6-6 of Fig. 2,

Fig. 7 is an enlarged detailed showing of the front seal roller applicator,

Fig. 8 is a transverse sectional view upon the line 8-8 of Fig. 7,

Fig. 9 is a front elevational view of the back seal applicator roller, and

Fig. 10 is a transverse sectional view upon the line 10-10 of Fig. 9.

Referring to Fig. 1, the main carrier cylindrical element A, as shown best in Fig. 2, is provided with a strip B, for applying gum to the front seal flap, C are strips for applying gum to the body flaps of the envelope, and D is a rectangular element for applying gum for attachment of the glassine or other transparent window.

The gum is applied to the strip B by the applicator E, which is fed from the box F, while the gum is applied to the strips C and to the window D by the applicators G and H respectively from the reservoir I.

The die cut envelopes, or other sheet materials to be gummed and/or imprinted, are held in the stack J and are removed one by one from the stack J by the sucker mechanism K (see also Fig. 4).

The gripper mechanism may function to grip

the form or blank S after it has been removed from the stack by the suction K.

The printing roller M may imprint the envelope, with ink supplied from the reservoir N, and after printing and gumming has been completed, the gripper mechanism P, carried by the belt Q, may take off the envelope and transfer it to the window patch applicator R.

Referring first to the partial cylindrical shell A provided with the gum applicator strips B, C and D, the main shaft 20 carries a plurality of hubs 27, 28, 29, 30 and 31, which carry a series of partial or fragmentary disk elements 22, 23, 24, 25 and 26.

The main cylindrical shell portion 21 is provided with the screw connections 32, 33, 34, 35 and 36 to the periphery of said disks.

It will be noted that the shell is cut off at 37 and the extensions of the disks 22, 23 and 24 carry the strip B by the screw or bolt connections 38.

The main shell 21 is also cut out at 39 and in the recesses formed there are positioned the strips C having the connections at 40 to the other ends of the peripheries of the segments 23 and 24. The square cut out 41 in the shell 21 receives the square applicator element 42 which is adjustably held in position by the slotted lugs 43 and the screws 44 upon the middle portion of the periphery of the segments 22 and 24.

As shown upon Fig. 3, the upper portions 78, 79 and 80 of the strips B, C and D are made of rubber, the upper surface of which is flush with the curved plate 21, said rubber surface taking up and carrying the gum to be applied to the envelope as shown at S in Fig. 5.

It will be noted that the combination A, B, C and D is so arranged to support and apply adhesive to the envelope blank S, as shown in Fig. 5.

The elongated end portions 45 of the shell correspond to the envelope body flaps 46.

The gumming strips C apply gum at 47 to the lower flap 48 of the envelope blank. The upper strip B applies gum at 49 to the front or main sealing flap 50, while the square strip D applies gum at 51 to around the window 52 in the envelope blank.

In practice, although the same gum may be utilized for application at 47 and 51, that is a non-edible slow drying gum or adhesive, which may slowly harden and acquire maximum adhesive properties even after being stacked, this gum should be quite different from the gum applied at 49, which must be an edible gum which has to be quick drying and which must be of such a nature as to be readily licked or moistened by the lips or tongue of a user.

It will be noted by reference to Fig. 3 that these plates A, B, C and D are of cylindrical contour and that the plates B and D, as well as the plates C (the last mentioned not being shown in cross section) are of adjustable construction, with the lower laminated plates 53 and 54 carrying the adjustable attachment lugs 43 and 56, which are held in position by the screws 44 and 38.

It is apparent that by changing the shape and adjusting the position of the elements A, B, C and D, that the machine may be made to accommodate any suitable size and shape of envelope blank, or it may be made to accommodate other forms of sheet material, which are to be gummed and/or imprinted.

The shaft 20, carrying the elements A, B, C and D, is driven by the main gear 57, which gear is timed with the gears driving the gum applicator

devices E, G and H (see particularly Figs. 1 and 7 to 9).

These applicators are for the purpose of applying gum to the strips B, C and D, which strips in turn will apply it to the back of the envelope blank or to the sheet material.

As shown in Fig. 1, the gum box F may contain a suitable fluid or heated adhesive or gum solution and it carries the shaft 58 on which rotates the fountain roller 59.

The frame of the machine indicated by the dot-and-dash lines 60, may also carry the shaft 58, as well as the main shaft 20.

The shaft 61 carries the first transfer roller 62 which picks up adhesive from the roller 59 and the shaft 63 carries the second transfer roller 64, which picks up adhesive from the first transfer roller 62. The transfer roller 64 will transfer the adhesive to the applicator E carried on the shaft 65.

The shafts 61, 63 and 65 may be mounted in the side frames 60 (see also Fig. 2). The applicator E, as shown in Fig. 7, carries a strip 66 which is provided with lugs 67 which are screwed at 68 to the body 69 of the applicator, which body 69 is carried on the shaft 65.

If desired all of the metal of the roller 63 might be cut away except that portion of the metal which carries the lugs 67. There should desirably be sufficient metal left also to support the strip 66.

As shown in Figs. 1 and 8, the segment 70 will usually be sufficient to support said strip. The rollers 58, 62 and 64 and the applicator E are usually so synchronized by gearing that the strip 66 will meet the strip B at each second revolution of the shaft 65 and will transfer gum from the box F to said strip.

The main gear 57, the pitch line of which is indicated at 57 in Fig. 1, turns in the direction 81 (see Fig. 1) and drives gears, the pitch lines of which are indicated at 82 and 83 on Fig. 1. These gears 82 and 83 are fixed to the shafts 65 and 84, respectively, and are positioned on the side of the frame 60.

The shafts 63, 61 and 58 are in turn driven in succession by gears (not shown) from the gear 82, while the shafts 76, 75 and 74 are in turn driven by gears (not shown) from the gear 83.

The shell structure A, B, C, and D and the applicator E could also be designed of sufficient diameter so that there would be a 1:1 ratio between the applicator E and the strip B, but it has been found desirable to decrease the diameters for the purposes of economy and to reduce the weight of the machine and permit the applicator E to make two revolutions for every one application of gum from the strip 66 to the strip B.

At the intermediate revolution the strip 66 will not be in contact with any portion of the shell A and will be ineffective on small size envelopes. Two shells with extra gripper can be installed.

In respect to the gumming of the strips C and D of Fig. 2, this gum is supplied from a fountain or box I, as shown in Fig. 1, through the fountain roll 71, the first transfer roll 72 and the second transfer roll 73 to the applicators G and H, these rollers respectively being provided with shafts 74, 75 and 76.

The applicators G and H, as shown in detail in Figs. 9 and 10, carry the curved bars 162, which apply gum to the strips C of the cylindrical structure A, and the frame 163 which applies gum to the frame D of the structure A. These elements 162 and 163 may be adjustably fixed by the set 75

screws 168 and 169 and the supporting structure 164 and 165 and the sleeves 166 and 167 upon the shaft 84 of the applicators.

As indicated in Fig. 1, the scrapers 85 and 86 scrape off the excess of gum from the rollers 59 and 71 and these scrapers are provided with adjustments. One of these adjustments is shown in Fig. 1, said adjustment consisting of an upwardly extending lug 87 provided with a screw 88, which is threaded into another lug 89 on the scraper 85.

After the plate A has been gummed by the applicators E, G and H, the envelope blank S is then applied thereto.

As shown in Fig. 1, the envelopes S are held in a frame V having the guide rods 90, and these envelopes are removed one by one by the sucker mechanism K. The sucker mechanism K, shown best in Fig. 4 and also in side view in Fig. 1 and in top view in Fig. 2, includes a hollow shaft 91 plugged as shown at 92 in Fig. 2 and containing the V-shaped sucker fingers 93.

These fingers 93 are each provided with an eye 94 fitting upon said shaft 91 and with an in-turned contact portion 95.

As shown best upon Fig. 2, the V-shaped members 93 are provided with bores 96 extending entirely therethrough. In operation, they are designed first to be moved in the direction 97 (see Figs. 1 and 2) guided by the stud shafts 98 which have reciprocatory or slide bearings in the collars 99 supported upon the frame structure 100.

The reciprocatory shafts 98 are connected at the eyes 101 to the ends of the sucker shaft 91 and they are provided with stop collars 102 designed to abut said collars 99. The position of the collars 102 may be adjusted by the lock nuts 103 (see Fig. 2).

The shaft 91 is caused to move in the direction 97 by the swinging bracket element 104 (see Fig. 4), which has a web 105 and is provided with an eye 106 carried on the shaft 107 and a downwardly extending rear member 108 terminating in the clevice 109 which receives the roller 110.

The roller 110 contacts the cam 111, which has the depressed portion 112 and the elevated portion 113.

As said main shaft rotates, the roller 110 will pass successively over the lower face 112 of the cam 111, in which case the sucker members 93 will be in their solid line position, as indicated in Fig. 4. When the roller 110 passes over the elevated portion 113, the presser foot 104 pressing against the roller 115 on the sucker shaft 91 will cause said shaft to move in the direction 97, compressing the spring 130, to bring said sucker heads 95 against the lowermost blank in the stack, indicated at S in Figure 1.

As soon as the sucker heads 95 have picked up the sheet, the roller 110 will move in the direction 116, the compressed spring 130 will expand and the sucker heads 95 will bring an envelope sheet, as indicated by the dot-and-dash lines at 117 (Figs. 1 and 3) against the plate A.

At this point the gripper L will function to grip the forward end of the paper blank S and at the same time the sucker elements K will be released by a suction cut off (not shown) at the right end of the shaft 91 and they will be moved out of path of rotation of the plate A. This suction cut off will operate when the suction mechanism is not operating to pick up a sheet S.

This last movement is done by the intermeshing segments shown best at T in end view in Fig. 1 and in top view in Fig. 2.

As indicated in Fig. 4, the main shaft 20 car-

ries a cam 118 having the depressed portion 119 and the elevated portion 120. This cam is provided with a follower roller 121, which is pivotally mounted in the clevice 123.

The clevice 123 forms part of a segment 124, which is pivotally mounted at 125 upon the side frame 60. The end of the segment is provided with the arcuate gear 126, which are shown as meshing with the gear teeth 127 on the half gear 128. The half gear 128 is provided with a hub 129, which fits upon and moves with the shaft 91 when the shaft 91 is moved in the direction 97. The gear teeth 126 and 127 then will be moved out of mesh. At this time the roller 122 will be riding over the low surface 119 of the cam 118, while the roller 110 is riding over the high surface 113 of the cam 111.

As soon as the roller 110 drops again onto the low surface 112 of the cam 111 and the spring 130 has returned the stud shaft 98 and the shaft 91 in the direction 116, the teeth 126 and 127 will be held in meshing position when the roller 121 is held against the low surface 119 by the spring 131 and when the shaft 91 is stopped by the pin 132 against the edge 133 of the cut-out 134 in the collar 101.

As soon as the teeth 126 and 127 have again intermeshed, the high portion 120 of the cam 118 will strike the roller 121 and will move the half gear 128 in the direction 135 (Fig. 4). This will be at greater speed than the cylindrical plate A moves and will cause the sucker fingers 93 to move down to dotted line position, as indicated at Fig. 4, out of the path of movement of the cylindrical plate A.

Simultaneously as the sucker fingers are released, the gripper shaft 136, which is carried with the main plate A and revolves with the rotation of the main shaft 20, will be turned in the direction indicated by the arrow 137. This in turn will turn the gripper element L, the collar 138 of which is fixed on said shaft 136, so that the contact finger portion 139 thereof will grip the portion 48 of the envelope blank S against the edge portion 140 of the plate A (see Figs. 2 and 3).

The gripper L will operate to hold the envelope in position on the plate A as it moves past the printing mechanism M and until the envelope blank is taken up by the conveyor chain or belt Q on which it is held by the gripper P.

This gripper mechanism L is actuated by the mechanism shown in Fig. 6 to grip the sheet at 48 when released by the sucker fingers 93 and to release the sheet just before the sheet is gripped by the gripper P.

Referring to Fig. 6, the gripper is shown in an upper position indicated by the arrow 137, in which it grips the envelope blank and a lower position indicated by the arrow 141, in which it is in off position.

The end of the gripper shaft 136 is provided with a pinion 142, which meshes with the rack 143 carried upon the arm 144. The arm 144 is provided with an eye 145 pivotally mounted at 146 upon the side of the main gear 57.

The left end of the arm 144 is provided with a clevice 147 (see also the left portion of Fig. 2) in which clevice the eye 148 is pivotally mounted by the pin 149. The eye 148 has a shank 150 carrying the lock nuts 151 and a rod extension 152 carrying the spring 153, which spring 153 reacts against the lug 154 pivotally mounted on the lower part of the side of the main gear 57, as shown.

The portion of the arm 144 adjacent the rack 143 carries a stud 155 with the roller 156, which roller is pressed against the dead cam 158 by the spring 153. The dead cam 158 is bolted or riveted at 159 (see also Fig. 2) to the side frame 60.

The cam 158 is provided with a high portion 160 which will cause the gripper L to be moved to gripping position in the direction indicated by the arrow 137 and the low portion 161, which will cause the gripper to be withdrawn to non-gripping position, as indicated by the arrow 141.

It will be noted that the entire assemblage of the pinion 142, the rack 143, the arm 144, the spring 153, the pivot 146 and the roller 156 rotate with the gear 57 and the shaft 20.

Referring to Fig. 1, the printing arrangement shown at the lower left hand of the figure, may consist of a fountain 170, in which is positioned the fountain roller 171, the transfer roller 172 and the actual printing roller 173, which should be of the embossed type and should not be of the intaglio type.

The rollers 171, 172 and 173 are respectively mounted on the shafts 174, 175 and 176. The shaft 174 is supported in the ear 177 of the fountain box 170 and the shaft 175 being supported by the arm or bar 178. The bar 178 is connected by a coil spring 179 to the frame 60 at 180 to draw the roller 172 against the roller 173.

The structure 181, forming part of the side frame 60, is designed to receive the bearing of the main printing roller 173, which is inked by the transfer roller 172.

If desired, several printing arrangements M—N may be positioned in parallel to print in different colors on different sides of the front of the blank S of Fig. 5, or by increasing the diameter of the shell A, it is possible to have several different printing rollers print in succession upon the blank.

The outside of the blank will always be exposed to the printing roller or rollers M. The blank which will now have been gummed at three different places for the front seal, the back seal, and the window piece and which will have been printed at the position M, will be carried on the shell A to adjacent the belt or chain Q where it will be picked up by the gripper finger P.

At this position the gripper finger 139 will be released by the roller 156 rising over the elevated position 160 of the cam 158 (see Fig. 6).

At the same time, by a mechanism not shown, the gripper finger P will be closed against the block 182 on its mount, said mount 183 and the block 182 being carried on the special links 184 and 185 forming part of a link chain 186, which constitutes the carrier belt Q. This link chain 186 acts as a sprocket which meshes with the teeth 187 of the sprocket wheel 188, which is rotatably mounted at 189.

This sprocket belt Q and gripper P will carry the imprinted blank S in the direction indicated by the arrow 190 between the rollers 191 and 192. These rollers 191 and 192 are pivotally mounted at 193 and 194 on the ear portions 195 and 196 of the frame 60 (see Fig. 1). The position of the blank is indicated by the dot and dash line 197. The shafts 193 and 194 are driven by the gear 201 from the gear 57.

The glassine or other transparent window material or patch is fed as a continuous strip at 198 intermittently between the cutting knives 199. As each patch is cut it will be laid onto the carrier R, the outline of which is the same as that

of the window and which is supported on a sector-like element 200.

The window patch is drawn against the face R by vacuum applied through the bore 202, which communicates with the hollow center portion 203 of the shaft 193.

At the point of application of the window carried on the applicator R to the imprinted blank S, it will come in contact with the pressure roller 192.

Instead of using the belt Q and the gripper P, it is also possible to use strippers to take off the imprinted blank from the shell A. The spacing between the center line of the shaft 20 and the shafts 193 and 194 is less than the length of the blank, so that it will be picked up between the applicator R and the roller 192 before it completely leaves the shell A.

In operation, before a blank is drawn from the stack S, as shown in Fig. 1, adhesive will be applied to the strips B, C and D, as shown in Fig. 2, by the applicators E, G and H.

As the adhesive is being applied, the cam 111, which turns with the main shaft 20, will be to press the tubular shaft 91 in the direction 97 and thus bring the sucker fingers 95 (see Figs. 1 and 4) against the stack J.

As soon as the roller 110 then goes over the depressed portion 112 of the cam 111, these fingers 95 will withdraw a single sheet or blank S from the stack as shown in Fig. 1, to the dotted line position shown in 117 and immediately the segment gear T will turn the partial gear 101 in opposite of the direction 135 and the sucker fingers 95 to the dotted line position as shown in Fig. 4. This will cause the sucker fingers 95 to release the blank S and move such sucker fingers out of the path of rotation of the shell A.

At the same time the roller 156 of Fig. 6 will drop onto the depressed portion 161 of the dead cam 158, causing the gripper finger 139 to move into the position shown in Fig. 3 (that is into the upper dotted line position shown in Fig. 6) to grip the blank which has now been drawn against the shell A.

The adhesive on the strips B, C and D will be applied to the back of said blank S against said shell A in the positions 47, 49 and 51, as shown in Fig. 5.

At the same time the printing roller M will imprint the envelope with suitable return address or other indicia or advertising material.

When the front edge of the blank S reaches directly below the shaft 20, the roller 156 of Fig. 6 will move onto the elevated portion of the dead cam 158, releasing the gripper finger 139 and the gripper finger P then will pick up the blank and pull it in the direction 199 to below the applicator R where the out window section or patch will be applied.

It is thus apparent that the present applicant has devised a simple, speedy, inexpensive apparatus for imprinting fluids, such as adhesives or inks, on opposite sides of a blank, particularly such as an envelope.

Although the apparatus is particularly designed for gumming the back side of an envelope and imprinting the front side, it is obvious it is also applicable to combine direct printing outside of the blank and offset printing inside of the blank operations where it is desired to obtain one type of imprinting upon one side of a blank and one type of imprinting on the other side of the blank.

The rotary apparatus will have a much greater speed of production than is possible with recipi-

rocatory apparatus and wide variation is possible in types of adhesives which may be applied by means of the offset process, with the use of a shell A.

5 The envelope after the window has been applied by the applicator R, may be folded and stored on suitable continuously moving racks so as to permit the adhesive to dry at 49, as indicated in Fig. 5 without having the flap contact 10 with the body of the envelope, while the body flaps of the envelope blank S will be pressed together to cause the adhesive at 47 to contact the end flaps 46 and dry slowly.

If desired, one of the patches of adhesive 47 15 might be omitted and adhesive coating at 48 shortened where penny saver envelopes are utilized, which are provided with side openings for mail inspection purposes.

After application of the window patch by the 20 rollers 191 and 192, the gummed and/or imprinted envelope blank is delivered to a mechanism folding and drying the envelope blank.

This rotary feeding gumming, printing and patching mechanism shown in the drawings, may 25 be sold as a unit and utilized most readily to replace the reciprocatory gumming mechanism of a plunger type machine.

If desired, the shell A might be duplicated with 30 small envelope blanks, in which case two blanks could be applied, one to each shell, during each revolution of the shaft 20. In this case each rotation of the applicators E, G and H would apply gum and the gripper mechanism L would be duplicated.

35 As many changes could be made in the gumming machine, and many apparently widely different embodiments of this invention could be made without departing from the scope thereof, it is intended that all matter contained in the 40 above description shall be interpreted as illustrative and not in a limiting sense.

What is claimed is:

1. In an envelope blank gumming and imprinting mechanism for simultaneously applying different types of gum to the side and end flaps of an envelope, a cylindrical carrier, a plurality of applicator means to apply said different types of gum to said carrier to be applied to said blank, a stack carrying envelope blanks, transfer means 50 to transfer one of said blanks from said stack to said carrier, said transfer means including rotatable suction fingers to withdraw one of said blanks from said stack and means to withdraw said suction fingers out of the way of said carrier 55 when one of said blanks has been removed from said stack and applied to said carrier, holder means to hold said blank on said carrier and remover means to remove said blank from said carrier after it has taken up said gum, said carrier being provided with segregated rubber faced areas to receive and apply the different types of gum to the desired areas on the envelope blank and said applicator means including rotatable elements having gum carrying areas approximating 60 the shape and size of the areas on the envelope blank to receive the gum, said applicator means and segregated areas being synchronized so that gum will only be applied to said segregated areas.

2. In an envelope blank gumming and imprinting mechanism for simultaneously applying different types of gum to the side and end flaps of an envelope, a cylindrical carrier, a plurality of applicator means to apply said different types of 70

gum to said carrier to be applied to said blank, a stack carrying envelope blanks, transfer means to transfer one of said blanks from said stack to said carrier, said transfer means including rotatable suction fingers to withdraw one of said blanks from said stack and means to withdraw said suction fingers out of the way of said carrier when one of said blanks has been removed from said stack and applied to said carrier, holder means to hold said blank on said carrier and remover means to remove said blank from said carrier after it has taken up said gum, said holder means including a swinging clamping finger and an actuator for said finger rotated with said carrier, said actuator having a secondary shaft carrying said finger, a pinion in the end of said shaft, a rack meshing with said pinion, an arm carrying said rack, a main gear for driving said carrier, pivotal mounts for said secondary shaft and arm on said main gear, a fixed cam and a follower carried by said arm to contact said cam.

3. In an envelope blank gumming and imprinting mechanism for simultaneously applying different types of gum to the side and end flaps of an envelope, a cylindrical carrier, a plurality of applicator means to apply said different types of gum to said carrier to be applied to said blank, a stack carrying envelope blanks, transfer means to transfer one of said blanks from said stack to said carrier, said transfer means including rotatable suction fingers to withdraw one of said blanks from said stack and means to withdraw said suction fingers out of the way of said carrier when one of said blanks has been removed from said stack and applied to said carrier, holder means to hold said blank on said carrier and remover means to remove said blank from said carrier after it has taken up said gum, said transfer means including reciprocably and rotatably mounted suction fingers, said suction fingers being provided with a shaft, a pusher member to push said fingers against said stack, a spring return to return said fingers, and a rotating arrangement to rotate said fingers after return out of the path of movement of said carrier.

4. In an envelope blank gumming and imprinting mechanism of the type having a cylindrical carrier, applicator means to apply gum to said carrier to be applied to said blank, a stack carrying envelope blanks, holder means to hold said blank on said carrier and remover means to remove said blank from said carrier after it has taken up said gum; transfer means to transfer one of said blanks from said stack to said carrier, said transfer means including suction fingers, a rotary shaft carrying said fingers, reciprocating shafts carrying the ends of said rotary shaft and bearings for said reciprocating shafts, and means to actuate said reciprocating and rotary shafts to move said suction fingers out of the path of said carrier after said transfer.

5. In an envelope blank gumming and imprinting mechanism of the type having a cylindrical carrier, applicator means to apply gum to said carrier to be applied to said blank, a stack carrying envelope blanks, holder means to hold said blank on said carrier and remover means to remove said blank from said carrier after it has taken up said gum; transfer means to transfer one of said blanks from said stack to said carrier, said transfer means including suction fingers, a rotary shaft carrying said fingers, reciprocating shafts carrying the ends of said rotary shaft and bearings for said reciprocating shafts,

and means to actuate said reciprocating and rotary shafts to move said suction fingers out of the path of said carrier after said transfer, said last-mentioned means including a shaft eccentrically carried by said carrier, and cams in said shaft to actuate said rotary and reciprocating shafts in a predetermined sequence.

6. In an envelope blank gumming and imprinting mechanism of the type having a cylindrical carrier, applicator means to apply gum to said carrier to be applied to said blank, a stack carrying envelope blanks, holder means to hold said blank on said carrier and remover means to remove said blank from said carrier after it has taken up said gum; transfer means to transfer one of said blanks from said stack to said carrier, said transfer means including reciprocably and rotatably mounted suction fingers, and recesses in said carrier to receive said suction fingers when said fingers are in their position closest to the carrier and means to reciprocate said fingers to carry one of said blanks from said stack to said carrier and then to rotate said fingers out of the path of said carrier.

7. In an envelope blank gumming and imprinting mechanism, a cylindrical carrier for the envelope blanks having segregated areas to receive and transfer different types of adhesive material onto the top and side flaps of the envelope and a plurality of applicator means having applicator rollers positioned so as to contact with said carrier at different places in its rotational movement, said applicator rollers respectively serving successively to apply different types of gum to said segregated areas, and means to apply an envelope blank to said carrier after said different types of gum have been applied thereto, whereby said envelope blank will be simultaneously gummed by different types of gum from said segregated areas.

8. A method of simultaneously applying different types of gum to the side and top flaps of an envelope blank, which comprises applying different types of gum to segregated areas of a cylindrical carrier, wrapping an envelope blank around said carrier to take up the different types of gum from said segregated areas and then removing said blank from said carrier after said envelope blank has taken up said gum from said segregated areas.

9. In an envelope blank gumming and imprinting mechanism for simultaneously applying different types of gum to the side and end flaps of an envelope, a cylindrical carrier, a plurality of applicator means to apply said different types of gum to said carrier to be applied to said blank, a stack carrying envelope blanks, transfer means to transfer one of said blanks from said stack to said carrier, holder means to hold said blank on said carrier and remover means to remove said blank from said carrier after it has taken up said gum, said carrier being provided with a cylindrical carrier face to receive and apply the different types of gum to the desired areas on the envelope blank and said applicator means including a plurality of rotatable elements to contact with said carrier face on each revolution thereof, said elements having gum carrying and applying areas approximating the shape and size of the areas on the envelope blank to receive the gum, said rotatable elements being positioned at different points in the course of travel of said carrier so as to successively apply to said carrier face gum in the areas corresponding in spacing

and size to the areas on the envelope blank which are to receive the gum.

10. A method of simultaneously applying different types of gum to the side and top flaps of an envelope blank, which comprises applying different types of gum to different areas on a cylindrical carrier, wrapping an envelope blank around said carrier to take up the different types of gum from said areas and then removing said blank from said carrier after said envelope blank has taken up said gum from said areas and imprinting the opposite side of the envelope blank at the same time it is wrapped around said carrier to take up said different types of gum.

11. In an envelope blank gumming and imprinting mechanism, a cylindrical carrier for the envelope blanks having segregated areas to receive and transfer different types of adhesive material onto the top and side flaps of the envelope and applicator means successively to apply different types of gum to said segregated areas, and means to apply an envelope blank to said carrier after said different types of gum have been applied thereto, whereby said envelope blank will be simultaneously gummed by different types of gum from said segregated areas and clamping fingers to hold said envelope blank upon said carrier.

12. In an envelope blank gumming and imprinting mechanism, a cylindrical carrier for the envelope blanks having segregated areas to receive and transfer different types of adhesive material onto the top and side flaps of the envelope and applicator means successively to apply different types of gum to said segregated areas, and means to apply an envelope blank to said carrier after said different types of gum have been applied thereto, whereby said envelope blank will be simultaneously gummed by different types of gum from said segregated areas, means to imprint the opposite sides of said envelope blank after it has been applied to said carrier and while it is still on said carrier and gripping fingers on said carrier to grip said blank upon said carrier after application to the carrier and during gumming and imprinting.

13. In an envelope blank gumming and printing mechanism, a recessed cylindrical carrier for the envelope blanks to receive and transfer adhesive material onto the top and side flaps of the envelope blank and applicator means to apply gum to said segregated areas, said gum being offset from said segregated areas onto a side of

said envelope blank, means to apply an envelope blank to said carrier after said gum has been applied to said carrier, gripping fingers to hold said envelope blank upon said carrier after application of said blank to said carrier and during the gumming of said blank from said carrier, and means to imprint the opposite side of said envelope blank from that applied to said carrier while it is still upon said carrier and while it is gripped by said gripping fingers.

14. A transfer device for transferring a sheet material from a stack of such sheet material to a carrying cylinder upon which said sheet materials are to be imprinted, which comprises a reciprocating carrier, positioned outside of said carrying cylinder, suction fingers rotatably mounted on said reciprocating carrier, means to reciprocate said carrier to cause said fingers to come in contact with said stack to remove a sheet of material from said stack and to carry said sheet of material to said carrying cylinder, said cylinder being recessed to receive said fingers when said fingers have moved said sheet against said cylinder and means to move said fingers when they have pressed said sheet against said cylinder to turn them out of the way of said cylinder.

15. A transfer device for transferring a sheet material from a stack of such sheet material to a carrying cylinder upon which said sheet materials are to be imprinted, which comprises a reciprocating carrier, including two side rods having slide bearings positioned on each side of said carrying cylinder, the forward ends of said side rods adjacent said carrying cylinder being provided with sleeve bearings, a rotatable tube mounted in said sleeve bearings connected to a source of suction, suction fingers mounted upon said rotatable tube and turning with said rotatable tube, means to reciprocate said side rods to cause said fingers to come into contact with said stack to remove a sheet of material away from said stack to said cylinder and to move said fingers carrying said sheet of material toward said cylinder to press said sheet against said cylinder, means to move said fingers out of the way of said cylinder when they have moved said sheet against said cylinder, and gripping fingers on said carrying cylinder to grip said sheet of material upon said carrying cylinder after said suction fingers have moved said sheet against said cylinder.

JOHN A. MATTERA.
